OPEN-WEB BEAM

Roy A. Badt, Los Angeles, Calif.

Application November 6, 1953, Serial No. 27,457

Term of patent 14 years

(Cl. D54—2)

Fig. 1

Fig. 2

Fig. 3

To all whom it may concern:

Be it known that I, Roy A. Badt, a citizen of the United States of America, residing at Los Angeles, in the county of Los Angeles, State of California, have invented a new, original, and ornamental Design for an Open-Web Beam, of which the following is a specification, reference being had to the accompanying drawing, forming a part hereof.

Figure 1 is a side elevational view of an open-web beam showing my new design;

Figure 2 is an enlarged fragmentary elevational view of an intermediate portion only of the open-web beam shown in Figure 1; and

Figure 3 is an end view of the open-web beam shown in Figure 1.

I claim:

The ornamental design for an open-web beam, as shown.
